Flexible Shaft Company, Chicago, Ill., a cor-
poration of Illinois

Application April 9, 1936, Serial No. 62,030

Term of patent 3½ years

To all whom it may concern:

Be it known that I, Ludvik J. Koci, a citizen of
the United States, residing at Chicago, in the
county of Cook and State of Illinois, have invented
a new, original, and ornamental Design for an
Electric Stove or Similar Article, of which the
following is a specification, reference being had
to the accompanying drawing forming part
thereof.

In the drawing:

Figure 1 is a perspective view of an electric
stove or similar article showing my new design;
Figure 2 is a top plan view thereof, and
Figure 3 is a side view thereof.

I claim:

The ornamental design for an electric stove or
similar article, substantially as shown.
